CLOSURE PLUG

Jeremiah J. Laurizio, Providence, N.J. (% American Flange & Mfg. Co. Inc., 30 Rockefeller Plaza, New York, N.Y. 10020)

Filed Nov. 11, 1974, Ser. No. 522,695

Term of patent 14 years

Int. Cl. D9—07

U.S. Cl. D9—288

FIG. 1 is a perspective view of a closure plug embodying my new design;

FIG. 2 is a further perspective view;

FIG. 3 is a top plan view; and

FIG. 4 is an elevational view.

I claim:

The ornamental design for a closure plug, substantially as shown.
